(57) **CLAIM**

The ornamental design for a head lamp for automobile as shown and described.

DESCRIPTION

FIG. 1 is a perspective view of the head lamp for automobile according to the present invention.

FIG. 2 is a front view of the head lamp for automobile of FIG. 1.

FIG. 3 is a rear view of the head lamp for automobile of FIG. 1.

FIG. 4 is a left side view of the head lamp for automobile of FIG. 1.

FIG. 5 is a right side view of the head lamp for automobile of FIG. 1.

FIG. 6 is a top view of the head lamp for automobile of FIG. 1; and,

FIG. 7 is a bottom view of the head lamp for automobile of FIG. 1.

The broken lines shown in the figures are for the purpose of illustrating portions of the head lamp for automobile and form no part of the claimed design.

1 Claim, 7 Drawing Sheets
